UNITED STATES PATENT OFFICE.

FRANK D. CHAPMAN, OF BERLIN, WISCONSIN.

IRONING MACHINE.

Application filed September 11, 1922. Serial No. 587,493.

REISSUED

To all whom it may concern:

Be it known that I, FRANK D. CHAPMAN, a citizen of the United States, and resident of Berlin, in the county of Green Lake and

5 State of Wisconsin, have invented new and useful Improvements in Ironing Machines, of which the following is a description, reference being had to the accompanying drawings, which are a part of this specification.

10 This invention relates to improvements in ironing machines and has for its principal object to provide a machine of this character which is especially adapted for household use.

A further object of the invention is to 15 provide an ironing machine which is relatively small and compact and in which the parts are so constructed and pivoted as to permit of its being folded, when not in use, to occupy a minimum amount of space.

20 A still further object of the invention is to provide a power driven machine having a plurality of rolls or mangles which may be heated by gas, steam, or other suitable medium, and which will be simple in construction, comparatively inexpensive to 25 manufacture, and more efficient in operation than those which have been heretofore proposed.

30 In the accompanying drawings in which like numerals designate like parts in all the views;

Figure 1 is a front view of a machine made in accordance with the present invention, a portion of the head or housing being 35 broken away to more clearly illustrate the interior construction, and the parts being shown in their operative positions;

Fig. 2 is a plan view of the parts shown in Fig. 1;

40 Fig. 3 is a view similar to Fig. 1 illustrating the parts in their folded positions;

Fig. 4 is a side elevational view of the parts shown in Fig. 1, as seen from the left of the said figure; and,

45 Fig. 5 is a side elevational view of the parts shown in Fig. 1 as seen from the right of the said figure.

Referring to the said drawings, it will be seen that the machine comprises a frame 50 composed of the horizontal members 10 and the upright members 11 and 12, the lower ends of the latter being secured in spaced relation to the members 10, while their upper ends are connected together as by bolts 13 forming a substantially triangular framework. The said members 10 are provided

with suitable rollers 14 whereby the device may be readily moved over the floor, as will be readily apparent.

The connections 13 serve as a pivot for 60 supporting the substantially triangular shaped auxiliary supporting frame or housing 15, to which is secured a suitable electric motor or other driving means 16, which is connected by means of a belt 17 to a pulley 18 carried by a shaft 19 suitably journaled in the said housing and carrying a worm 20 which meshes with a worm gear 21 rigidly mounted upon a shaft 22 extending at right angles to the shaft 19, see Figs. 70 1 and 3.

The said shaft 22 carries a pinion 23, which meshes with a gear 24, mounted upon a shaft 25, journaled in the said casing or housing in parallel relation to the shaft 22. 75 The shaft 22 is further supported by means of an inclined bracing member or link 26, see Fig. 1, while the shaft 25 is likewise further supported by means of the bracing member or link 27.

The said shafts 22 and 25 respectively carry the rolls or mangles 28 and 29, the former of which is preferably hollow, as indicated, to accommodate one end of a pipe 30 which serves as a burner pipe for the combustion of gas or liquid fuel within the said roll 28. The said pipe may be supported by means of a bracket 31 secured to the bracing link 26 and the flow of the gaseous or liquid fuel therethrough, or of the steam 90 where the latter is employed for heating purposes, may be controlled by means of the valve 32. The casing 15 may be provided with a door 33 to permit access to its interior for inspection, repair, or lubrication of 95 the parts therein.

Suitably supported beneath the mangles or rolls 28 and 29, as by the bracket 35 and the inverted U-shaped member 36, is a table 37 which is adapted to support the work 100 during the ironing operation.

In order to control the pressure between the rolls 28 and 29, the latter of which is preferably covered with cloth or other fabric, the link member 27 is connected to a collar 38 which is mounted upon the shaft 25 and which permits rotation of the said shaft therein. The said link member 27 is also provided with a pin 39 which is adapted to be engaged by the socket 40, 105 see Fig. 3, of the upwardly extending rod 41, the lower end of which is connected to 110

a lever or arm 42 rigid with a rock shaft 43, which also carries a foot treadle or lever 44, see Figs. 4 and 5.

It thus results that when the foot treadle 5 or lever 44 is depressed the motion is transmitted through the rock shaft 43 and lever arm 42 to the upwardly extending rod 41 which exerts a pressure upon the pin 39, thereby causing the link member 27 and collar 38 to tend to press the shaft 25 and roll 29 upwardly, thus increasing the pressure of the said roll 29 against the roll 28, as will be readily apparent.

In order to permit a slight relative movement between the rolls 28 and 29, the shaft 25 may be pivotally mounted in the casing 15, as at 45. It will be understood, however, that the relative movement is not great enough to disengage the gears 24 and 23 20 or to cause them to bind.

The foot treadle 44 is provided with a latch 46 having a plurality of notches or indentations 47 which are adapted to engage a pin 48 when it is desired to maintain a constant pressure between the rolls 28 and 29. A spring 49 is provided which tends to normally maintain the said notches out of engagement with the said pin and this spring will release the latch 46 whenever a slight pressure is applied thereto and then removed.

As above stated it is one of the primary objects of this invention to provide a mechanism which may be folded up in order to 35 occupy a minimum amount of space, and, as was above described, the casing or housing 15 is pivotally connected to the framework by the bolts 13. In order to maintain the parts in the operative positions illustrated in Figs. 1, 2, 4, and 5, there is provided a latch 50 mounted upon the upright members 11 and adapted to engage a portion of the casing 15, as will be clear from Fig. 1.

When it is desired to fold up the machine, 45 the catch 51 with which the table 37 is provided, is released from the bracket 35, thereby permitting the said table to pivot upon its U-shaped support 36 and to drop downwardly. The latch 50 is then released 50 permitting the casing 15 and the mangles or rolls 28 and 29, as well as the burner pipe 30, to move in a clockwise direction about the pivot bolts 13 to the positions indicated in Fig. 3. It will of course be understood 55 that a suitable flexible connection is provided between the burner pipe 30 and the source of the fuel supply in order that the said pipe may swing, as just described.

It will thus be seen that this invention 60 provides a relatively small and compact

ironing machine suitable for household use and which may be folded up when not in use to occupy a relatively small space.

It is obvious that those skilled in the art 65 may vary the details of construction as well as the arrangement of parts without departing from the spirit of the invention, and therefore it is not wished to be limited to the above disclosure except as may be required by the claims. 70

What is claimed is:

1. An ironing machine comprising a frame; a housing; a pair of pressure rolls rotatably carried by said housing; a motor also carried by said housing for rotating said 75 rolls; means for heating said rolls; a horizontal pivotal connection between said frames and housing, said housing, together with the parts carried thereby, being movable about said pivotal connection from an 80 operative horizontal extended position to an inoperative compact vertical position within said frame; and means engaging said frame and housing to maintain the parts in their 85 operative positions. 85

2. An ironing machine of the class described comprising a supporting frame; an auxiliary supporting frame pivotally secured to said first frame; a pair of substantially parallel disposed rolls mounted in said auxiliary frame; link connections between said auxiliary frame and one of said rolls whereby said roll may be adjusted toward and from its companion roll; foot actuated means engaging said link connections for 90 causing said adjusting movements; a motor also carried by said auxiliary frame; and constantly engaged driving connections between said motor and said rolls. 95

3. An ironing machine of the class described comprising a main supporting frame; an auxiliary supporting frame pivotally secured to said main frame; a pair of substantially parallel disposed rolls mounted in said auxiliary frame, one of 100 said rolls being relatively fixedly journaled in said frame; link connections between said auxiliary frame and the other of said rolls for floatingly mounting said roll in said frame for movement toward and from its 105 companion roll; foot actuated means readily detachably engaging said link connections for causing said movement; a motor carried by said auxiliary frame; and constantly engaged driving connections between said 110 motor and said rolls. 115

In testimony whereof, I affix my signature.

FRANK D. CHAPMAN.
